UNITED STATES PATENT OFFICE.

WILLIAM H. HOGAN, OF BOSTON, MASSACHUSETTS, ASSIGNOR OF ONE-HALF
TO EDWARD W. PASTURE, OF SAME PLACE.

COMBINED BOUQUET AND TICKET HOLDER.

SPECIFICATION forming part of Letters Patent No. 295,870, dated March 25, 1884.

Application filed May 14, 1883. (No model.)

To all whom it may concern:

Be it known that I, WILLIAM H. HOGAN, a citizen of the United States, residing at Boston, in the county of Suffolk and State of Massachusetts, have invented a new and useful Combined Cutter, Bouquet-Holder, and Ticket-Holder, of which the following is a specification.

My invention consists of a device embodying the several elements of a bouquet-holder, a card or ticket holder, a cutter for cord, twine, &c., and a twine or string carrier, and also an eyeglass-holder, the device being designed for attachment to the lapel of a coat, a vest, or other convenient portion of the dress.

Referring to the accompanying drawings, Figure 1 represents a blank of sheet-brass or other metal, of which the main portion of the device consists. Fig. 2 is a front view of the device with all the parts together. Fig. 3 is a side view of the same. Fig. 4 is a bottom edge view of the plate when bent into shape. Fig. 5 is a view of a detached portion of the device. Fig. 6 is an enlarged view of the same. Fig. 7 is a view of another detached portion.

Similar letters indicate like parts in the several figures.

In carrying out my invention, I first cut or strike out a blank of sheet-brass or other sheet metal, as shown in Fig. 1, and then bend over the ends *b b* and the portion *c* to the shape shown in Fig. 4, and turn down the part *d*, to form a hook.

Fig. 5 represents a wire having its two ends sharpened to allow of their being readily stuck into the cloth of a dress, and is formed with two legs, *e e*, or prongs. The center *g*, constituting the head, is bent to form one complete coil or loop. Then each end or leg is bent up to follow the form of the coil *g* as far as the center, and then up straight, as shown at *f f'*, as high as the top of the coil *g*. The ends are then bent backward, so as to leave a space between the parts *f f'* and the ends forming the legs or prongs *e e*. This portion, which may be called the "pin" or "holder," being all in one piece, is connected to the hook *d* by passing one of the ends into the hook and turning it so as to bring the hook to the position shown in Fig. 2. The legs *e e* are normally sprung apart, as seen in Fig. 5, and, when the loop is attached to the hook *d*, the

legs *e e* are placed within the bent-over ends *b b* of the plate or shield *a*, whereby the two parts are held together. When attached to the dress, the legs *e e* are first passed through the cloth and then secured in the bent portions *b b*. The part *c* of the shield or blank *a* is bent over in the shape shown in Fig. 4. Within this bent-over part *c* is fixed one end of a blade or cutter, *h*, the sharp edge of which is at the inner side, and the outer end is raised sufficiently to allow of a string, cord, or twine to be inserted at the upper end and readily cut.

Fig. 7 represents an eyeglass-holder. It is made of a single piece of wire, the horizontal end *j* of which passes through the bent portion *c* and blade *h*, serving as rivet to the blade, and allowing of a slight movement of the blade. This holder is bent in the form shown in Fig. 7, the central portion, *l*, passing upward and somewhat inward, forming a tongue narrower than the back portion, *i k*, upon which tongue may be hung an eyeglass or glasses. The side *i* passes by and bears against the cross-piece *j*, by which it is held in position. When used as a bouquet-holder, the stem or stems of the flowers are passed through the loop *g*. The loop is also useful for holding the end of cord or twine carried about the person. The cutter is useful for persons engaged in tying up packages, &c. A car-ticket may be held between the pins *e e* and the shield *a*.

What I claim as my invention, and desire to secure by Letters Patent, is—

1. A bouquet and ticket holder and cutter consisting of the shield *a*, the holder *g f f' e e*, the cutter *h*, and the hold *k i j l*, substantially as and for the purpose set forth.

2. The combination of the holder composed of the loop *g*, the bent portions *f f'*, and legs *e e* with the shield *a*, provided with the hook *d* and bent portions *b b*, the shield being of a single metal plate, all as shown and described.

In testimony whereof I have signed my name to this specification in the presence of two subscribing witnesses.

WILLIAM H. HOGAN.
